Patented Apr. 18, 1922.

Inventor
John M. Lipes

UNITED STATES PATENT OFFICE.

JOHN M. LIPES, OF DAYTON, OHIO.

DESIGN FOR A FISHING REEL.

60,867.

Specification for Design. Patented Apr. 18, 1922.

Application filed July 15, 1921. Serial No. 485,108. Term of patent 3½ years.

To all whom it may concern:

Be it known that I, JOHN M. LIPES, a citizen of the United States, residing at 281 Delaware Ave., Dayton, in the county of Montgomery and State of Ohio, have invented a new, original, and ornamental Design for Fishing Reels, of which the following is a specification, reference being had

to the accompanying drawing, forming part thereof.

The figure is a perspective view of a fishing reel showing my new design.

I claim:

The ornamental design for a fishing reel, as shown.

JOHN M. LIPES.
